UNITED STATES PATENT OFFICE.

ARTHUR E. BARLOW, OF WORCESTER, MASSACHUSETTS.

COP AND COP-HOLDER FOR WIRE-NETTING MACHINES.

No. 875,404.

Specification of Letters Patent.

Patented Dec. 31, 1907.

Application filed July 6, 1905. Serial No. 268,463.

To all whom it may concern:

Be it known that I, ARTHUR E. BARLOW, a citizen of the United States, residing at Worcester, in the county of Worcester and 5 State of Massachusetts, have invented a new and useful Cop and Cop-Holder for Wire-Netting Machines, of which the following is a specification.

This invention relates to that class of machines which are employed for making "chicken coop" wire netting.

The especial object of this invention is to provide a strong, simple and efficient form of cop and cop-holder having means for locking the same in place against accidental displacement, and which are pivoted so that they can turn with comparatively little friction.

To these ends this invention consists of the 20 cop and cop-holder and of the combinations of parts therewith as hereinafter described and more particularly pointed out in the claims at the end of this specification.

In the accompanying drawing, Figure 1 is 25 a transverse sectional view of sufficient parts of a wire netting machine to illustrate the application of this invention thereto. Fig. 2 is an enlarged sectional view partly broken away of sufficient parts of a machine to illustrate the application of a cop and cop-holder thereto. Fig. 3 is a side view of the cop partly broken away. Fig. 4 is a side view of the cop-holder partly broken away. Fig. 5 is a fragmentary view similar to Fig. 2 showing 30 the locking catch unfastened so as to permit the cop and cop-holder to be inserted into or taken out of the machine, and Fig. 6 is a detail view of a division piece for the cop showing a guide piece for the wire.

40 In machines which are used for making the so-called "chicken coop" netting, one half of the wires are taken from reels or other sources of supply, while alternate wires are furnished from cops or bobbins. The cop-holders are mounted in bearings in top and bottom twisting gears. The top and bottom twisting gears are made in half sections and are shifted transversely between the making of successive twists, so that a wire from any 45 one cop is twisted alternately with the reel wires at the sides thereof. In this class of machines the cops and cop-holders are the parts which give the most trouble. In most of the machines the cop-holders are simply 50 dropped into place in bearings in the twisting gears, and it sometimes happens that a num-

ber of such cop-holders will become displaced from their bearings and will drop out of position in the machine, requiring the stopping of the machine and the replacement of the parts. In these machines, also 60 the cops and cop-holders must be mounted so that they will turn readily upon their bearings, permitting wires to be supplied as fast as required without breaking or kinking. 65

In a wire netting machine equipped according to this invention each of the cop-holders is held in place in its bearings by means of a simple and efficient locking device which will prevent the cop-holder from 70 being accidentally displaced, while permitting it to be readily unlocked and taken out whenever the cop or bobbin thereof requires refilling. The cop and cop-holder are supported upon a step bearing which is preferably 75 provided with a bearing ball in an oil socket which contains sufficient oil to keep the bearing well lubricated.

Referring to the accompanying drawing for a detail description of a cop and cop-holder constructed according to this invention, and of sufficient parts of a wire netting machine to illustrate the application of this invention thereto, as shown in Fig. 1, A designates one of the end frames of a wire netting machine. Mounted upon and supported by the frames A are fixed top and bottom gear rails R and R'. Coöperating with the fixed gear rails are movable gear rails M and M'. Mounted in the rails R and M are the 80 top split twisting gears, one-half of each of which receives one of the reel wires, and the other half of each of which is provided with a downwardly extending bearing S for engaging the top of a cop-holder. Mounted in 85 the rails R' and M' are the bottom split twisting gears one-half of each of which receives one of the reel wires W, and the other half of each of which is provided with an upwardly extending step S' for supporting the cop and 90 its holder. The netting as fast as made is fed out by a feed roll F, and may be rolled up or delivered in any of the usual ways. The parts as thus referred to may be of any ordinary or usual construction and need not be 95 herein described at length.

The cop and its holder which I have devised is most clearly illustrated in Figs. 2 to 6 inclusive. As shown in these figures, the cop-holder consists of a tube 10 having an 100 upper slot 11 and a lower slot 12. These slots are provided for the purpose of permitting

the operator to see where the wire is, and for convenience in threading the wire into place. Mounted in the tube 10 and pinned rigidly in place therein is a division piece 13. Mounted in a socket in the piece 13 is a spring-pressed pin 14 which is held in place by a cover-plate 15. Pivoted on the cover-plate 15 is a bell-crank locking lever 16, one leg of which is engaged by the spring-pressed pin 14. At its upper end the tube 10 of the cop-holder fits onto the bearing S. The cop or bobbin as herein illustrated, comprises a tube or bobbin 17 having a head 18 at its upper end. The bobbin head 18 is provided with a pivot pin or pindle 19 engaging the center hole of the division piece 13. Fastened in the lower end of the pipe 17 is a step 20 which is provided with a counter-sunk socket for resting on a bearing-ball 21 mounted in an oil well in the step S'. The wire W' which is wound on the bobbin extends out through the slot 11 as shown in Fig. 1, and in passing the collar or piece 13 the wire W' preferably runs in a guide piece 22 illustrated in Figs. 4 and 6. It is shown extending out through the slot 11 for convenience only, as in practice the wire does not project through the slot in this way. The guide piece 22 consists of a small trough-shaped piece of hardened steel which may be fastened in place by one or more screws 23. The guide piece 22 is preferably highly tempered, so that it will not be worn or cut by the wire which is drawn up through the same.

In the operation of a netting machine equipped according to this invention, whenever it is desired to remove a cop and its holder, the locking lever 16 may be released by inserting a rod through the upper part of the slot 11, and when the locking lever is released the cop and the cop-holding tube may be lifted as shown in Fig. 5, so that said parts may be taken out from the machine, and if desired a new cop-holder inserted.

When the parts are in normal position, as illustrated in Fig. 2, the cop and cop-holder will be securely locked in place so that they cannot be accidentally displaced, while the weight of each cop and its cop-holder rests upon a thoroughly lubricated bearing ball so that the same can be readily turned without breaking or kinking the wire.

I am aware that various changes may be made in the construction of my cop and cop-holder in applying them to different makes and arrangements of wire netting machines. I do not wish, therefore, to be limited to the construction I have herein shown and described, but

What I do claim and desire to secure by Letters-Patent of the United States is:—

1. In a wire netting machine, the combination of a cop, a cop holder, and a locking device for the holder comprising a bell-crank mounted in the upper part of the holder and

adapted to engage a bearing extending down from an upper twisting gear to lock the holder against a rising motion in the bearings.

2. In a wire netting machine, the combination of a cop, a cop-holder, and a locking device in the upper part of the cop-holder for preventing the holder from being accidentally raised from a bearing in the bottom twisting gear.

3. In a wire netting machine, the combination of a tubular cop-holder having its upper end embracing a bearing extending down from an upper twisting gear, a cop fitting into the cop-holder and having its lower end mounted in a step in the bottom twisting gear, and a locking device co-operating with the bearing extending down from an upper twisting gear for preventing said parts from being displaced from their bearings.

4. In a wire netting machine, the combination of a tubular cop-holder embracing a bearing extending down from a top twisting gear, means for supporting the cop-holder from a bearing in a bottom twisting gear, and a locking device holding said parts in place and consisting of a catch preventing the cop-holder from being raised except when said catch is unlocked.

5. In a wire netting machine, the combination of a tubular cop-holder having a piece therein dividing the cop-holder into two parts or chambers, the upper one containing a locking catch for preventing the cop-holder from being raised except by unlocking the catch, and the lower part being adapted to receive a bobbin or cop.

6. In a wire netting machine, the combination of a tubular cop-holder having a division piece therein dividing the cop-holder into two parts or chambers, the upper part or chamber containing a spring-pressed bell-crank shaped catch for preventing the cop-holder from being lifted to be removed from the machine except when the catch is unlocked, a cop or spool having a bearing at its upper end in the division piece of the cop-holder and having a bearing piece at its lower end for engaging a bearing ball mounted in an oil-filled socket in a step extending up from a bottom twisting gear.

7. In a wire netting machine, the combination of a tubular cop-holder having a division piece dividing the cop-holder into upper and lower chambers, a spring-pressed bell-crank shaped catch mounted in the upper chamber of the cop-holder for preventing the cop-holder from being lifted except when the catch is released, a cop mounted in the other chamber of the cop-holder and having a step bearing in a bottom twisting gear, and a hardened steel guide piece for guiding the wire as it is drawn from the cop up past the division piece of the cop-holder.

8. In a wire netting machine, the com-

5 bination of a cop holder having a division piece dividing it into upper and lower chambers, a cop mounted in the lower chamber of the holder, and a hardened steel 5 guide piece for guiding the wire as it is drawn from a cop up past the division piece of the holder, said guide-piece having a slot for permitting the wire to pass.

9. In a wire netting machine, the combination of a cop-holder having a division 10 piece therein dividing the holder into two parts or chambers, a spring-pressed locking catch in the upper chamber preventing the cop-holder from being lifted to be removed

from the machine, and a cop or spool having 15 a bearing at its upper end in the division piece of the cop-holder, and having a bearing at its lower end for engaging a bearing mounted in a socket in a step extending up from a bottom twisting gear. 20

In testimony whereof I have hereunto set my hand, in the presence of two subscribing witnesses.

ARTHUR E. BARLOW.
